UNITED STATES PATENT OFFICE.

EDWIN J. SHEFFIELD, OF CAMBRIDGE, MASSACHUSETTS.

HAIR-WAVING DEVICE.

1,101,100.

Specification of Letters Patent. Patented June 23, 1914.

Application filed July 30, 1913. Serial No. 782,088.

To all whom it may concern:

Be it known that I, EDWIN J. SHEFFIELD, a citizen of the United States, and resident of Cambridge, in the county of Middlesex and State of Massachusetts, have invented certain new and useful Improvements in Hair-Waving Devices, of which the following is a specification.

This invention relates to hair-waving devices.

Of the accompanying drawings, which illustrate the preferred form of the invention, Figure 1 represents a perspective view in which the device is shown opened. Fig. 2 is a side elevation of the device in open position. Fig. 3 is an elevation similar to Fig. 2, showing the device flexed as if by closing pressure. Fig. 4 is an elevation showing the device closed. Fig. 5 is a view similar to Fig. 4, including a hand holding the device as if to open it.

The same reference characters indicate the same parts wherever they occur.

The device is made of a strip of suitable springy material bent at 10 to provide a bar 11 and a bar 12. The strip is also bent at 13 to provide a lip 14 adapted to overlap and coat with the tip of the bar 11 to hold the bar 11 as shown by Figs. 4 and 5. The device is intended to be used by coiling the hair around the bar 11 and then placing the tip of said bar in coactive engagement with the lip 14, as shown by Figs. 4 and 5. The bent strip may be made of spring steel or celluloid or any other suitable material. A tubular jacket 15 of suitable material, such as cloth or leather, may be slipped upon the bar 11 to protect the hair from being cut by the edges of the bar 11. The bar 11 is normally straight, or approximately so, and the bar 12 is normally bowed outwardly to facilitate the opening and closing of the device. The device may be closed by pressing the two bars toward each other, as indicated by arrows in Fig. 3. Such pressure first carries the tip of the bar 11 against the outer side of the lip 14, and further pressure has the effect of straightening the bar 12 and increasing its effective length sufficiently to carry the tip of the lip 14 beyond the tip of the bar 11, so that the two tips may pass each other. When the two tips have passed each other, the bar 12 automatically resumes its normal state of curvature whereby the

lip 14 is moved toward the bend 10 and 55 overlaps the tip of the bar 11. The device will automatically spring open when the bar 12 is straightened enough to disengage the lip 14 from the tip of the bar 11. No lateral flexure is necessary, either for closing 60 or opening the device.

Fig. 5 shows one way of grasping the device to open it when it is in use. The ends of the device are supported by a thumb *a* and head represented by dotted line *b*. A 65 finger *c* is upon the curved bar 12 which is uppermost. If the finger *c* now presses downwardly, the bar 12 will be straightened. This will carry the lip 14 beyond the tip of the bar 11, and the latter will be released. 70 As the bar 11 is straight throughout its length and has no projection or other formation which could catch the hair, the hair would preferably be coiled about this bar.

Although I have shown a guard 15, I do 75 not wish to have it understood that the device is inoperative without such a guard, as obviously the edges of the bar 11, if smooth and not too sharp, would not injure the hair. It should also be understood that the 80 invention is not limited to the described method of operating it, and that the reason for describing in what manner the device may be opened and closed is to illustrate the facility with which it is adapted to be operated with one hand.

I claim:

A hair-waving device consisting of a strip of thin flat springy material having a transverse bend near its middle and two coactive 90 bars diverging therefrom, one of said bars being substantially straight and the other being bowed outwardly, the free end of said bowed bar being turned back to form a lip, the free end of said straight bar engaging 95 the inner face of said lip when the parts are in closed position, the lip being movable longitudinally away from the free end of said straight bar when the device is supported at its ends and pressure applied to 100 the bowed portion.

In testimony whereof I have affixed my signature, in presence of two witnesses.

EDWIN J. SHEFFIELD.
